United States Patent Office.

VIRGIL W. BLANCHARD, OF BRIDPORT, VERMONT.

Letters Patent No. 96,871, dated November 16, 1869.

IMPROVEMENT IN PRESERVING FRUITS, MEATS, AND OTHER SUBSTANCES.

The Schedule referred to in these Letters Patent and making part of the same.

To all whom it may concern:

Be it known that I, VIRGIL W. BLANCHARD, of the town of Bridport, in the county of Addison, and State of Vermont, have invented certain new and useful Improvements in the Mode of Preserving Fruit, Meat, and other substances; and I do hereby declare that the following is a full, clear, and exact description thereof, reference being had to the accompanying drawings, and to the letters of reference marked thereon, which form a part of this specification, and in which—

Figure 1 represents a longitudinal section of my device for preserving fruit, &c., and

Figure 2, a side elevation of the stopper.

Similar letters indicate like parts in both figures.

This invention consists in an improved mode of preserving fruit, meat, and other substances from the oxidizing effects of the atmosphere, by enclosing the same in an air-tight vessel, into which there is introduced a chemical agent whose affinity for oxygen is so great as to entirely remove it from the air contained in said vessel, leaving the material to be preserved in a bath of almost pure nitrogen-gas.

To enable others skilled in the art to which my invention appertains, to make and use the same, I will now describe its construction and operation.

In the accompanying drawings—

A represents a vessel or jar for holding the substance to be preserved. This may be of any desirable size or shape.

B represents a cover, provided with the rubber packing C for closing the mouth of the vessel A, and making an air-tight joint.

D represents a rim, perforated with holes attached to the under surface of the cover B, and provided with the stud E.

F represents a cup sliding over the rim D, and secured thereon by means of a right-angled slot cut in its upper margin, and the stud E.

G represents a sponge or any other suitable packing, occupying the cup F.

H represents a bottle containing a specimen of pyrogallic acid.

I represents a bottle containing a specimen of liquor potassa.

K is a bottle containing a specimen of an alkaline solution of pyrogallic acid, formed by mixing certain proportions of water and liquor potassa with pyrogallic acid.

In the practical operation of this invention, the substance to be preserved is put into the vessel A. Then, for every cubic inch of air that the vessel A may con-

tain after the substance or liquid to be preserved is introduced, from one to three grains of pyrogallic acid should be introduced in the cup F, and sufficient water added to dissolve it. Then a sufficient quantity of liquor potassa should be added to the solution, to render it alkaline, when the sponge G should be introduced into the cup F, and the latter secured to the rim D. Then the cover B should be applied to the mouth of the vessel A, closing it air-tight.

By means of the sponge G, the alkaline solution of pyrogallic acid is brought into contact with the oxygen contained in the air in the cup F, removing it therefrom by its chemical affinity for the same.

The oxygen contained in the air outside of the cup F, in the vessel A, passing into the cup through the perforations in the cup F in the vessel A, passing into the cup through the perforations in the rim D, in obedience to the elemental law of diffusion of the gases, becomes absorbed in a similar manner, until the oxygen is entirely removed from the interior of the vessel A.

If the substance is to be preserved for a great length of time, it is economical to add a sufficient quantity of pyrogallic acid to the cup F not only to remove the oxygen from the air contained in the vessel A, but to deoxidize any air that might enter the same in consequence of leakage. It will be seen that the contents of the cup F are secured from passing into the vessel A by being held in the sponge G.

By the means described, it will be seen that fruit, meat, and other substances may be preserved from the oxidizing effects of the atmosphere for a greater or less length of time, without resorting to the injurious mode of applying heat or any other means that injures their flavor or texture.

Having thus fully described my invention,

What I claim as new, and desire to secure by Letters Patent, is—

1. The use of an alkaline solution of pyrogallic acid, substantially as and for the purpose set forth.

2. The combination of the cover B, elastic packing C, movable cup F, and sponge G, or their equivalents, substantially as and for the purpose described.

3. The combination of the vessel A, cover B, elastic packing C, cup F, sponge G, and the alkaline solution of pyrogallic acid or its equivalent, substantially as and for the purpose set forth.

In testimony that I claim the foregoing as my own, I affix my signature, in presence of two witnesses.

VIRGIL W. BLANCHARD.
